UNITED STATES PATENT OFFICE.

ALBERT MOSHEIM, OF EAST ORANGE, NEW JERSEY.

DESIGN FOR COMPACT CASE.

Application filed March 3, 1925. Serial No. 12,553. Term of patent 3½ years.

To all whom it may concern:

Be it known that I, ALBERT MOSHEIM, a citizen of the United States, residing at 81 Harrison Street, East Orange, New Jersey, have invented a new, original, and ornamental Design for Compact Cases, of which the following is a specification, reference being had to the accompanying drawing, forming part thereof.

In the drawing:

I claim

The ornamental design for compact case, as shown.

ALBERT MOSHEIM.
